(57) **CLAIM**

The ornamental design for a composite fragrance bottle, as shown and described.

DESCRIPTION

FIG. 1 is a top, front, right side perspective view of my new design for a composite fragrance bottle;

FIG. 2 is a front elevation view of the fragrance bottle shown in FIG. 1;

FIG. 3 is a right side elevation view of the fragrance bottle shown in FIG. 1, the left side being a mirror image thereof;

FIG. 4 is a rear elevation view of the fragrance bottle shown in FIG. 1;

FIG. 5 is a top plan view of the fragrance bottle shown in FIG. 1;

FIG. 6 is a bottom plan view of the fragrance bottle; and,

FIG. 7 is an exploded view of the fragrance bottle shown in FIG. 1, showing the separation of the composite fragrance bottle into two cooperating fragrance bottles.
